MANUALLY OPERATED KNITTING MACHINE

Jacob Michalinsky, Brooklyn, N. Y.

Application September 28, 1949, Serial No. 118,244

13 Claims. (Cl. 66—4)

1

This invention relates to improvements in knitting machines, particularly those of the portable and manually operable type.

The principal object of the invention is to provide a faster and more easily operated knitting machine of the class mentioned than has been known heretofore.

Another object of the invention is the provision of a machine in which a long series of loops or stitches can be produced at one stroke.

Another object of the invention is to construct the knitting mechanism in such manner that it can be adjusted to provide for loops or stitches of varying lengths.

Still another object of the invention is to provide a generally improved knitting machine.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the carrying case for the machine of the invention.

Fig. 2 is a general perspective view of the machine of the invention.

Fig. 3 is a detail plan view of a turn table utilized by the invention.

Fig. 4 is a general plan view of the knitting mechanism of the invention.

Fig. 5 is a left-hand end elevation of the mechanism of Fig. 4.

Fig. 6 is a right hand end elevation of the mechanism of Fig. 4.

Fig. 7 is the same view as Fig. 5 but with certain of the parts in an operated position.

Fig. 8 is a fragmentary detail view from underneath of a latching device of the invention.

Fig. 9 is an isolated detail view in perspective of a hook member of the invention.

Fig. 10 is a fragmentary sectional view of the mechanism on line 10—10 of Fig. 4.

Fig. 11 is a fragmentary, partly sectioned view in perspective of parts of the mechanism shown in Figs. 4 and 5.

Fig. 12 is a perspective of a plow cam utilized by the invention.

Fig. 13 is a sectional view on line 12—12 of Fig. 4.

Fig. 14 is an isolated perspective of a pair of restoring bars utilized by the invention.

Figs. 15, 16, 17 and 18 are sectional views of the mechanism on lines 15—15, 16—16, 17—17.

2

and 18—18 of Figs. 19, 20, 21 and 22, respectively, and serve along with the latter figures to illustrate the four steps in the operation of the machine.

5 Figs. 19, 20, 21 and 22 are fragmentary plan views of the knitting mechanism during the four stages of its operation.

Fig. 23 is a perspective view, partly broken away, of a modified knitting machine.

10 Fig. 24 is a left-hand end elevation of the machine of Fig. 23.

Fig. 25 is a plan view, partially broken away, of the device of Fig. 23.

15 The knitting machine of the invention is conveniently housed in a carrying case 25 (Fig. 1) constructed of wood or some other substantial material and comprising a box-like cover 26 (Fig. 2) provided at either end with carrying straps 27 (Fig. 1) and a bottom or base board 28 removably fastened to the cover in any suitable way.

20 The knitting mechanism is secured in place on base 28 between longitudinal beams 30 and lateral bars 31, but before entering into a detailed description of said mechanism it is deemed desirable to describe first the role played by the cover 26 in the operation of the machine.

25 The longitudinal side walls of cover 26 are provided near their mid-points each with a plurality of spaced pairs of screws 32 (Figs. 1 and 2) which act to support a partition board 33 placed therebetween. At the center of its upper edge partition 33 is provided with a pivot screw adapted to receive a turn table comprising a pair of sheet

30 metal plates 34 (see also Fig. 3) connected together at their four corners by screws 35 in such manner that the plates can be drawn together or spaced farther apart by manipulation of the screws. To prevent the turn table from flying off the pivot screw, the latter is provided with a wing nut 36. Four yarn receiving arms 37 have their inner ends looped each about one of the screws 35, said screws being tightened down to hold arms 37 in place by the pressure of plates

35 40 thereon. At their outer ends arms 37 are suitably bent to support and guide a loop of yarn 38, said yarn passing from said loop through a guide member 40 removably mounted in one end of cover 26, and over to the knitting mechanism which is placed in close proximity thereto. There

45 50 also may be provided a second guide member mounted in the other end of the cabinet but this latter member is not shown.

The knitting mechanism is mounted on a base plate 41 secured on base board 28 between beams

30 and bars 31 (Figs. 4 and 10), and its framing comprises a longitudinal center bar 42 connected at either end to lateral frame bars 43. The outer face of each bar 43 is provided with a pair of plates 44 (Figs. 4, 5 and 11) which are secured to the bar by screws 45, said screws passing through slots 46 in the plates in order to make the latter adjustable laterally to vary the length of the stitches as will become apparent hereinafter. Each plate is also provided with a bearing notch 47 to receive one of the trunnions 48 in the ends of a pair of rocking cross bars 50 to be more fully described hereinafter. Mounted on each plate 44 for fore and aft sliding movement thereon is a slide 51 having at one end an open end slot 52 (Fig. 11) adapted to receive the end of trunnion 48, and at the other end an ear 53 for manual manipulation of the slide. The slide is mounted on plate 44 by means of a screw 54 in the latter playing in a slot 55 in the former, and can be moved to the position shown in Figs. 5, 6 and 7 where its slot 52 embraces trunnion 48 and retains the latter in notch 47 (Fig. 11), or to the position shown in Fig. 11 where slot 52 is free of the trunnion to allow rocking cross bar 50 to be removed from the machine.

The outer longitudinal edge of each of the rocking bars 50 has secured thereto a backing strip 56 (Figs. 4 and 11), and the inner portion of the upper edge of each of said bars has a retaining strip 57 fastened thereon, the latter strip being of sufficiently greater weight than the former to unbalance the bar and cause its inner edge to rock downward for reasons to become apparent hereinafter, however, it is desired that each of the bars 50 rock only at certain appropriate times, and to prevent its rocking at other times each bar 50 has a latch lever 58 pivoted to its underside at 60 (Figs. 4 and 8), said lever being urged by a spring 61 into engagement with a lip 62 formed on the right-hand end (Fig. 4) frame bar 43 (see also Figs. 5 and 7). When it is desired to rock either bar 50 the lever 58 associated therewith is moved free of lip 62 and the bar allowed to rock by its own unbalanced weight.

Each of the rocking bars 50 is provided with a long series of equispaced grooves 63 (Fig. 16) extending from backing strip 56 to the inner edge of the bar beneath retaining strip 57. Each of these grooves has slidably mounted therein a hook member 64 (Figs. 9 and 13), said member being provided at its inner end with a hook portion 65 and at its outer end with a restoring ear 66 extending laterally therefrom above bar 50. In the normal position of the members 64 shown in Fig. 13 the outer ends thereof abut the backing strips 56 and the hooks 64 stand just forward of the retaining strips 57.

In order to prevent the oppositely disposed hooks 65 from sliding inward and banging against one another when the machine is not in use, and also to move all of said hooks to their advanced or to their restored positions simultaneously, there are provided two restoring bars 67 (Fig. 14) which are placed in contact either with the restoring ears 66 or the outer edges of the hooking member as the occasion demands, and are drawn by hand to the desired position.

In order to restore advanced hook members 64 individually one after the other there is provided a plow cam 68 (Fig. 12) having a shouldered lip 70 to engage one or the other of the retaining strips 57 (Fig. 17) along which the cam is pulled by means of a handle 71, the incline 72 of the cam engaging the restoring ears 66 of the hook

members in succession and restoring them to normal position.

Midway between the hooks 65 is the center bar 42 which has a headed pin 73 projecting from its upper edge between each longitudinal pair of hooks 65 (Fig. 10). The center bar 42 is also provided at each end with an eye screw 42a (Figs. 4 and 10) through one of which the yarn 38 can be guided in its path to the knitting mechanism, and on the other of which the free end of the yarn is tied.

Mode of operation

The first step in the preparation of the machine for knitting is to wind the yarn in a loop on arms 37 (Fig. 2), the free end of the yarn being passed through guide 40 and over to the knitting mechanism where it is guided by one of the eye screws 42a and tied to the other (Figs. 4 and 11).

The next step is to lock the rocking bars 50 in their normal position by means of levers 58 (Figs. 4, 5 and 8), and to move all of the hooking members 64 to their retracted positions (Fig. 11) with the aid of restoring bars 67 (Fig. 14). The machine is then in condition to commence knitting operations in the manner now to be described.

In the following discussion it will be assumed for brevity and clarity of description and illustration that the knitting operation is to be performed on a partially completed piece of knit goods 74 (Figs. 15-22).

The piece of goods 74 is laid atop one of the bars 50 (Figs. 15 and 19) and the end loops 75 thereof slipped over the headed pins 73.

The first step of the operation consists in tilting the other (not the one on which the piece of goods was placed) bar 50 downward as shown in Figs. 15 and 19 and placing the anchored length of yarn 38 atop knit goods 74, adjacent the pins 73.

The second step is to advance by means of one of the bars 67 (Fig. 14) all of the hook members 64 carried by the tilted bar 50 (Fig. 15) and to rock the bar back to its horizontal position by means of the appropriate lever 58 (Fig. 8), thus bringing the hooks 65 of said members into position to engage the length of yarn 38 (Figs. 16 and 20).

The third step consists in engaging the shouldered lip 70 of cam 68 with the retaining strip 57 and pulling said cam along said strip to restore the advanced hook members 64 to normal position (Figs. 17 and 21), the hooks 65 of said members each pulling with it between the adjacent pins 73, a section of the length of yarn 38, which by the fourth step in the operation becomes a new end loop.

The fourth step is to tilt bar 50 again to free the hooks 65 from the length of yarn 38, and to flap the piece of goods 74 over on to the tilted bar, knit goods 74 (Figs. 18 and 22) being pulled slightly to slip the end loops 75 free of pins 73 and on to the sections of yarn 38 previously pulled by hooks 65. This, of course, forms a series of new end loops 76.

The tilted bar 50 is then rocked back to its normal horizontal position and step one, above, repeated and so on.

When the operation is not one of finishing a partly completed piece of goods but rather one of beginning a new piece, there is of course no end loops 75 to slip over pins 73. In this case the yarn is looped about each of the pins to form a series of first loops. The operation from this

point onward, however, is identical with that described above.

It is believed evident that the lengths of the loops 75, 76 can be varied simply by adjusting plates 44 (Fig. 5) laterally so as to vary the point to which the hooks 65 are restored with the sections of yarn 38.

Referring to Figs. 23, 24 and 25, there is illustrated therein a simple modified form of the invention. This machine comprises a base plate 80 upon which there is mounted between angle bars 81 and 82 a center board 83 having its upper edge rounded and studded with a series of equispaced headed pins 84. Center board 83 is embraced at either end by a sheet metal strap 85 which at its upper ends is suitably formed to provide bearings for two cylindrical bars 86 and 87. Each of the bars 86 and 87 is provided with a series of headed pins 88 having the same spacing as pins 84 but each being located midway between each pair of the latter. At diagonally disposed ends the bars 86 and 87 are prolonged past the bearing strips 85 to provide for their being manipulated by hand. Each of the bars 86 and 87 is maintained in its normal position with the pins 88 vertical by a stud 90 in its prolonged end engaging in an open end slot 91 in bearing strip 85, the stud being maintained in the slot by a compression spring 92 enclosed in the other bearing strip 85 and pushing on the bar.

The operation of this device is substantially identical with that of the one described above, the end loops of the material being slipped over the center pins 84 and the bars 86 and 87 rocked by hand to advance and restore the pins 88 which act in the same manner as the hooks 65 hereinbefore described.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a portable, manually operable knitting machine, the combination of a fixed center bar, a series of equispaced headed pins projecting upward from said bar, a pair of rocking bars one on either side of said center bar and a series of hook members slidably mounted on each of said rocking bars, said hook members having the same spacing as said headed pins but each being located midway between two of said pins.

2. In a portable, manually operable knitting machine, the combination of a fixed center bar, a series of equispaced headed pins projecting upward from said bar, a pair of rocking bars one on either side of said center bar and each unbalanced to tilt downward at the edge proximate the center bar, a latch to prevent each said bar from tilting.

3. In a portable, manually operable knitting machine, the combination of a fixed center bar, a series of equispaced headed pins projecting upward from said bar, a pair of rocking bars one on either side of said center bar and each unbalanced to tilt downward at the edge proximate the center bar, a latch to prevent each said bar from tilting, a trunnion in either end of each of said rocking bars, a bearing plate for each trunnion and having a notch in its upper edge to receive the latter, each said bearing plate being adjust-

able laterally, and a slide mounted on each bearing plate and having in its end an open end slot to receive the trunnion borne by the latter, said slide holding the trunnion in its bearing notch.

5. 4. In a portable, manually operable knitting machine, the combination of a fixed center bar, a series of equispaced headed pins projecting upward from said bar, a pair of rocking bars one on either side of said center bar and a series of hook members slidably mounted on each of said rocking bars, said hook members having the same spacing as said headed pins but each being located midway between two of said pins, a restoring ear on each of said hook members, and a restoring bar for each series of hook members to restore or advance the latter simultaneously.

5. 5. In a portable, manually operable knitting machine, the combination of a fixed center bar, a series of equispaced headed pins projecting upward from said bar, a pair of rocking bars one on either side of said center bar and a series of hook members slidably mounted on each of said rocking bars, said hook members having the same spacing as said headed pins but each being located midway between two of said pins, a restoring ear on each of said hook members and a plow cam to engage said ears and restore the hook members individually one after the other.

30. 6. In a portable, manually operable knitting machine, the combination of a fixed center bar, a series of equispaced headed pins projecting upward from said bar, a pair of rocking bars one on either side of said center bar and a series of hook members slidably mounted on each of said rocking bars, said hook members having the same spacing as said headed pins but each being located midway between two of said pins, a restoring ear on each of said hook members, a restoring bar for each series of hook members to restore or advance the latter simultaneously, and a plow cam to engage said ears and restore the hook members individually one after the other.

7. 7. In a portable, manually operable knitting machine, the combination of a carrying case comprising a box-like cover and a bottom board, a fixed center bar mounted on said bottom board, a series of equispaced headed pins projecting upward from said bar, a pair of rocking bars, one on either side of said center bar, and a series of hook members slidably mounted on each rocking bar, said hook members having the same spacing as said headed pins but each being located midway between two of said pins.

55. 8. In a portable, manually operable knitting machine, the combination of a carrying case comprising a box-like cover and a bottom board, a fixed center bar mounted on said bottom board, a series of equispaced headed pins projecting upward from said bar, a pair of rocking bars, one on either side of said center bar, and a series of hook members slidably mounted on each rocking bar, said hook members having the same spacing as said headed pins but each being located midway between two of said pins, a removable center partition for said cover, a pivot screw projecting upward from said partition, and a turn table including arms to support a loop of yarn pivoted on said screw.

60. 9. In a portable, manually operable knitting machine, the combination of a carrying case comprising a box-like cover and a bottom board, a fixed center bar mounted on said bottom board, a series of equispaced headed pins projecting upward from said bar, a pair of rocking bars, one on either side of said center bar and each unbalanced to tilt downward at the edge proximate the center bar, a latch to prevent each said bar from tilting, a trunnion in either end of each of said rocking bars, a bearing plate for each trunnion and having a notch in its upper edge to receive the latter, each said bearing plate being adjust-

on either side of said center bar, and a series of hook members slidably mounted on each rocking bar, said hook members having the same spacing as said headed pins but each being located midway between two of said pins, a removable center partition for said cover, a pivot screw projecting upward from said partition, and a turn table removably mounted on said pivot screw, said turn table comprising two plates adjustably spaced apart by corner screws, and a plurality of yarn supporting arms each having one end looped about one of said screws and fastened between said plates, and the other end formed to support a loop of yarn.

10. In a portable, manually operable knitting machine, the combination of a carrying case comprising a box-like cover and a bottom board, a fixed center bar mounted on said bottom board, a series of equispaced headed pins projecting upward from said bar, a pair of rocking bars, one on either side of said center bar, and a series of hook members slidably mounted on each rocking bar, said hook members having the same spacing as said headed pins but each being located midway between two of said pins, a removable center partition for said cover, a pivot screw projecting upward from said partition, and a turn table removably mounted on said pivot screw, said turn table comprising two plates adjustably spaced apart by corner screws, and a plurality of yarn supporting arms each having one end looped about one of said screws and fastened between said plates, and the other end formed to support a loop of yarn, and one or more guides for said yarn removably mounted on said cover.

11. In a portable, manually operable knitting machine, the combination of a carrying case comprising a box-like cover and a bottom board, a fixed center bar mounted on said bottom board, a series of equispaced headed pins projecting upward from said bar, a pair of rocking bars, one on either side of said center bar, and a series of hook members slidably mounted on each rock-

ing bar, said hook members having the same spacing as said headed pins but each being located midway between two of said pins, a removable center partition for said cover, a pivot screw projecting upward from said partition, and a turn table removably mounted on said pivot screw, said turn table comprising two plates adjustably spaced apart by corner screws, and a plurality of yarn supporting arms each having one end looped about one of said screws and fastened between said plates, and the other end formed to support a loop of yarn, and one or more guides for said yarn removably mounted on said cover, a guide for said yarn at one end of said center bar and an anchor for said yarn at the other end of said center bar.

12. In a portable manually operable knitting machine, the combination of a fixed center bar, a series of equispaced headed pins projecting upward from said bar, a pair of rocking bars, one on either side of said center bar, and a series of hook members mounted on each of said rocking bars and projectable between said pins one series at a time.

13. In a portable manually operable knitting machine, the combination of a fixed center bar, a series of equispaced headed pins projecting upward from said bar, a pair of rocking bars, one on either side of said center bar, and a series of hook members mounted on each of said rocking bars and projectable between said pins one series at a time, and a bar to project or restore all of the hook members of a series, simultaneously.

JACOB MICHALINSKY.
